P. P. Ruger,
Splitting Wood.
No 22,750. Patented Jan. 25, 1859.

UNITED STATES PATENT OFFICE.

PHILIP P. RUGER, OF NEW YORK, N. Y.

MACHINE FOR SPLITTING WOOD.

Specification of Letters Patent No. 22,750, dated January 25, 1859.

To all whom it may concern:

Be it known that I, PHILIP P. RUGER, of the city, county, and State of New York, have invented certain new and useful Improvements in the Construction of Wood-Splitting Machines; and I do hereby declare the following is a description of my said improvements, referring to the accompanying drawing, in which—

10 Figure 1 is an elevation with the side removed. Fig. 2, is an isometrical view of the guide-plate for the knives.

My improvements consist in certain details of construction by which I cheapen 15 certain well known features of wood splitting machines used for various purposes, and render them more certain in action while I provide against the injuries arising to the machinery from accidental displacement of the wood and other causes.

The construction is as follows: A proper framework *a* is made of sufficient size and strength for the purpose. This sustains a permanent horizontal trough *b* through 25 which the wood slides on its end. At each end of the trough there is a carrying roller *c c'* placed horizontally around which at each side of the trough there is an endless chain *d* that runs close to the side of the trough 30 in a recess or otherwise supported a proper distance above the bottom by guides on which it runs. The two chains *d* one on each side have bars *e* extending across from one to the other at right angles to them 35 which sweep over the bottom of the trough but sufficiently high therefrom to carry forward the blocks of wood placed thereon. Bars similarly arranged and operated have before been used but they were placed so low 40 as to constantly be tripping the blocks and allowing them to fall, and they could not be elevated or they would be broken or damaged by the machine if anything lodged on them. To remedy this difficulty and at 45 the same time elevate properly the cross bars I introduce a spring *f* just at the splitting point where the knives are playing and in this way relieve the cross bars *e* from all danger of breakage for if a block chances 50 to ride them they are forced down upon the bottom of the trough, the springs *f*

yielding for the purpose, and no damage occurs therefrom. This is very essential to the well working of the machine. Instead of springs any other yielding device 55 may be used to produce the effect.

In all the machines heretofore made for splitting wood there is a more or less expensive arrangement of slides, and cross heads affixed to the knives, instead of all of 60 which I cast an iron guide plate, shown at Fig. 2, *x*, and through it form holes or oblong slits *i* just sufficient for the knives to play through and at the ends or angles of these slits I cast in one piece with the plate 65 upright ways *y* that project up perpendicularly from the upper side of the plate and serve as slide ways to guide and steady the knives. These form permanent and cheap fixtures to hold the knives in place and give 70 them a true direction while splitting wood. The knives are worked up and down by a lever *l* of the second order the fulcrum of which is at *m* in the uprights of the frame, they being connected therewith by connect- 75 ing rods *n*. A crank *k* coupled with the motive power and attached to the end of the lever or working beam *l* by pitman *p* gives motion to the machine. A counter weight attached to the opposite end of the working 80 beam balances the parts and gives ease to the motions. The chains are moved at intervals by ratchet and pawl *z* of ordinary make which are well known devices and no particular description is necessary. 85

Having thus fully described my improvements what I claim and desire to secure by Letters Patent is—

1. The spring or yielding guide for relieving the cross bars *e* in the manner specified and for the purpose set forth. 90

2. I also claim the guide plate *x* with the uprights *y* constructed and arranged in combination with the woodsplitter as hereinbefore specified. 95

In witness whereof I have hereunto set my hand.

PHILIP P. RUGER.

In presence of—

Ed. BEKEWITZ,
D. D. WRIGHT.
